UNITED STATES PATENT OFFICE.

FRANK H. PECK, OF JAMESVILLE, NEW YORK.

SAMPLER.

1,072,644.

Specification of Letters Patent.

Patented Sept. 9, 1913.

Application filed May 13, 1913. Serial No. 767,247.

To all whom it may concern:

Be it known that I, FRANK H. PECK, of Jamesville, in the county of Onondaga, in the State of New York, have invented new 5 and useful Improvements in Samplers, of which the following, taken in connection with the accompanying drawings, is a full, clear, and exact description.

This invention relates to certain improvements in samplers and pertains more particularly to a device for sampling cement, grain or other loose material adapted to be deposited or confined in bins or retaining receptacles of some depth.

10 It is well known among those familiar with the manufacture, storing and handling of cement, grains, etc., that it is very difficult to determine the condition or quality of the material at various depths, or to obtain 15 samples of the material for inspection or examination by prospective purchasers.

The primary object, therefore, of this invention is to produce a simple and efficient device which may be used for obtaining 20 samples of loose materials of various kinds, at any desired depth of the material and which may be constructed with a minimum of expense and material.

Devices of this kind have been constructed 25 of two telescoping tubes or sleeves having openings adapted to register in a predetermined position and one rotatable within the other for moving the openings in the respective tubes out of registration with each 30 other. In this class of devices, however, it is impossible when buried in a mass of material, to determine the exact position of registration of the openings or the exact position when the openings are out of registration 35 and the chamber closed, and unless the chamber is tightly closed when the device is withdrawn with its sample of material, the utility is destroyed for the reason that grain or cement from different stratas 40 will fall into the chamber and mingle with the sample.

A further object, therefore, of my invention is to provide means for positively closing said chamber, operable in such a manner 45 that the operator will know that the chamber is closed although it is out of sight, by providing upon the inner or telescoping sleeve a projecting flange adapted to engage the outer sleeve when the chamber is closed.

50 In the drawings—Figure 1 is a front view of my sampler. Fig. 2 is a cross section on

line 2—2, Fig. 1. Fig. 3 is a cross section on line 3—3, Fig. 1. Fig. 4 is a cross section, similar to that shown in Fig. 3 except the opening into the chamber is shown as 60 closed. Fig. 5 is a perspective view of the inner or telescoping sleeve.

The device comprises a cylindrical tube 65 —1—, preferably formed of sheet metal, having hollow frusto-conical sections —2— and —3—, preferably formed of sheet metal, attached to its respective ends, in any suitable manner as soldering, and adapted to form with the tube —1— an elliptical chamber. The outer end of the frusto-conical section —2— is somewhat elongated and externally threaded for receiving an extension bar —4— having a hollow internally threaded end —5—. For preventing relative rotation of these parts when in the 70 desired position, I have provided a set screw —6— adapted to bear against the threaded portion of the section —2—. In like manner the outer end of the section —3— is somewhat elongated and externally 75 threaded for receiving a point or spear —7— having an internally threaded portion, and in like manner I have provided the spear —7— with a set screw —8— adapted to bear against the threaded portion of the section 80 —3— for preventing relative rotation of these parts.

The tube —1— is provided with an opening —9—, preferably rectangular in shape and vertically arranged with respect to the 90 tube, as shown, and with an inner telescoping cylindrical member or sleeve —10—, preferably formed of sheet metal, and of substantially equal extent with the tube —1— and having an opening —11— of substantially the same size as the opening —9— in the tube —1— and preferably formed by cutting away a portion of the sleeve upon three of its sides and bending it back along the remaining attached side to form a projecting flange —12— and this flange —12— is adapted to lie in and project from the opening —9— in the tube —1—, the extent of this projection —12— depending largely upon the consistency and weight of the material in which it is designed to operate, and it will be apparent that this projection may be formed in the manner above described of almost any extent without affecting the operability of the device, for the reason that 100 the portion of the sleeve —10— which closes the opening —9— lies behind the flange and 110

the extent of the opening in the sleeve —10— will not in any way affect the size of the opening —9— unless the flange —12— be of less extent than the width of the opening —9—.

The extension rod —4— may be of any desired length, depending upon the depth of the material in which the device is to operate, and is preferably provided with 10 a handle or operating member —13— attached thereto in any suitable manner.

When the device is inserted in a mass of cement, grain or other loose material, the spear or point —7— makes a passageway 15 for the rest of the device, which is, of course, inserted with the chamber in closed position, as shown in Fig. 4. When the desired depth is attained, the handle —13— is turned, whereby the outer tube —1— is rotated. The flange —12— on the sleeve —10— frictionally engages the cement, grain or other material and prevents rotation of the sleeve so that rotating the handle —13— counter-clockwise, in Fig. 1, causes 20 the openings —9— and —11— to register and material may enter the chamber formed by the sections 1, 2 and 3, respectively. The flange —12— not only prevents rotation of the sleeve —10— but also engages the edge 25 of the tube —1— surrounding opening —9— and prevents further rotation of the sleeve —10—. By turning the handle —13— in the opposite direction, the tube —1— is turned back again, the sleeve —10— being 30 stationary until the other edge of the opening —9— engages the flange —10— and the opening —9— is closed. Further rotation 35

of the handle —13— tends to close the opening more tightly.

The device may then be withdrawn from the material and will contain a true sample 40 from the depth desired. It is readily apparent that the section —3— may terminate in a point and that the spear or point —7— may be omitted without departing from the 45 spirit of my invention, as set forth in the appended claim.

It is further apparent that the sleeve —10— need not be cylindrical or circular in cross section, but may be any arc of a circle 50 of sufficient extent so that the portion upon either side of the flange thereon slightly exceeds in width, the width of the opening in the outer sleeve.

What I claim is:

In a sampler, a substantially cylindrical sleeve having an opening through a wall thereof, a flange projecting from the sleeve adjacent said opening, an outer section enclosing said sleeve and forming a chamber 60 extending above and below the same and having an opening through a wall thereof and through which the flange upon the sleeve is adapted to extend, said outer section having a point at its lower end, and 65 means in connection with said section adapted to extend above the material to be sampled for rotating said section.

In witness whereof I have hereunto set my hand this 7th day of May 1913.

FRANK H. PECK.
